UNITED STATES PATENT OFFICE.

DAVID M. CARO, OF MONTCLAIR, NEW JERSEY.

SHARPENING DEVICE.

1,066,094.

Specification of Letters Patent.

Patented July 8, 1913.

Application filed October 9, 1912. Serial No. 784,691.

To all whom it may concern:

Be it known that I, DAVID M. CARO, a citizen of the United States, residing in Montclair, in the county of Essex and State of New Jersey, have invented new and useful Improvements in Sharpening Devices, of which the following is a specification.

This invention relates to devices for sharpening cutting instruments, such as the removable blades of razors and the like, and it is the primary object of the invention to provide a device of this character which is simple and cheap in construction and efficient in operation.

15 A further object of the invention is to provide a device of this character which is not only adapted to sharpen blades having only one cutting edge, but it is also particularly adapted to sharpen blades having a double cutting edge, that is, cutting edges on opposite edges of the blade, and to simultaneously sharpen both edges.

Further objects and advantages will hereinafter appear.

25 In carrying out the above objects I provide two pairs of superposed abrasive rolls synchronously rotated through suitable gearing actuated by a crank connected to one of the rolls, a blade carrying rocker extending longitudinally between the rolls having cam followers to engage with a cam connected to and rotatable with one roll of each pair to cause one side of a cutting edge to engage with one roll of a pair alternately 30 with the engagement of the opposite side of the cutting edge with its companion roll, means being provided to increase or decrease the pressure with which the blade engages with the rolls; said rolls and blade carrier 35 are journaled in a casing consisting of a pair of hinged sections with one roll of each pair journaled in each section, whereby the sharpening mechanism and blades are entirely enclosed during the sharpening operation preventing any liability of the accidental injury 40 of the operator.

In the drawing accompanying and forming a part of this specification, Figure 1 is a side elevation, partly in section, illustrating an embodiment of my invention, and illustrating in dotted lines the tilting of the hinged section backward. Fig. 2 is a longitudinal sectional view taken substantially on the line A—A through the casing of Fig. 1 and through one of the rolls. Fig. 3 is a sectional end elevation taken on the line

B—B of Fig. 2. Fig. 4 is a perspective view of a blade carrier for carrying one form of blade having a double cutting edge. Fig. 5 is a perspective view of a modified form of blade carrier for carrying a blade having a single cutting edge; and Fig. 6 is an end elevation of the blade carrier shown in Fig. 5, illustrating a blade in section therein.

Similar characters of reference designate like parts throughout the different views of the drawing.

In the drawing I have illustrated an embodiment of my invention, comprising two pairs of superposed rolls 7, 7' and 8, 8' fixed to axles 9, 9' and 10, 10' whereby they are journaled in a casing consisting of a section 11 in which the rolls 7' and 8' are mounted and a section 12 hinged to the section 11 in which the rolls 7 and 8 are mounted for a purpose to be hereinafter described. The rolls are covered with a suitable abrasive material 13, preferably leather, as shown in Fig. 2. The rolls are synchronously driven through a train of gearing, comprising pinions 14, one fixed to the axle of each roll and actuated by a crank 15 fixed to the axle of the roll 8' outside of the casing.

A carrier for the blades to be sharpened comprises a bar 15 to extend longitudinally of and between the rolls, as shown in Figs. 1 and 3, said bar having reduced ends, as at 16, whereby it is supported in recess portions in the casing section 11 with the ends engaging in openings in spring clips 17 fixed to the outside of the case. This bar may be provided with projections 18 for supporting a blade 19, such for instance as the "Gillette" razor blade having two cutting edges and provided with the usual openings in which these projections may engage. The blade is retained in position by a spring clip or pin passing through a transverse opening in the central pin. These carriers may be interchangeable and are readily removable by pressing outward on the clips 17, as shown in dotted lines in Fig. 2, releasing the same. When supporting a razor blade, as 19', having only one cutting edge this bar may be provided with a spring clip 20, 105 (Figs. 5 and 6,) with the blade clamped between said clip and the bar as clearly shown in said figures.

To rock the carrier and thereby the razor so as to alternately present one side of the cutting edge to the action of one roll of a pair and then the opposite side of the cut-

ting edge to its companion roll, I provide said carrier with a pair of oppositely extending arms 21 which are in the nature of cam-follower adapted to engage with cams 22, 23 fixed to the rolls and rotatable therewith, in the present instance the rolls 7' and 8'. To compensate for wear of the abrasive or leather covering of the rolls, and to regulate the pressure with which the 10 blade engages with the rolls, I provide the cam-follower arms with adjustable means to engage with the cams, in the present instance consisting of set screws 24 engaging with the cams 22, 23.

15 The operation of my improved device is substantially as follows: Assuming it is desired to sharpen a razor blade having two cutting edges of the "Gillette" type. The cover section of the casing is tilted backward as shown in dotted lines in Fig. 1, when the blade is adjusted on the carrier pins 18. The cover section is now again caused to engage with the lower section 11 and retained in such position by a spring 20 catch 25. By rotating the crank in the direction of the arrow the rolls through the gearing are rotated in the direction of the arrows or outward from the cutting edges of the blade. As the crank is rotated one 25 catch 25. By rotating the crank in the direction of the arrow the rolls through the gearing are rotated in the direction of the arrows or outward from the cutting edges of the blade. As the crank is rotated one side of one cutting edge of the blade is caused to engage with the roll 8 while the opposite side of the opposite cutting edge is caused to engage with the roll 7'. This engagement takes place for substantially 30 180 degrees of revolution, when the opposite sides of the cutting edges are caused to engage with the rolls 7, 8' during the succeeding 180 degrees of revolution, and vice versa. The forcible engagement of the blade with 35 the rolls is caused by the timing of the cams 22, 23. When the cam-follower screw is on the high portion of the cam 23, the cam-follower screw for the other cam 22 is on the low portion, and vice versa, as clearly illustrated in Figs. 1 and 3. In order to remove 40 the blade the cover section 12 is again tilted up when the blade may be readily removed and another substituted. When sharpening blades having only one cutting edge the carrier shown in Fig. 5 is utilized. To remove or substitute a blade the entire carrier may be removed, which can be readily done by 45 releasing the spring clips 17.

To prevent retrograde or reverse move-

ment of the crank and thereby of the rollers, 55 with consequent result of cutting the leather covering of the rolls, I provide a ratchet wheel 26 on the axle of the roll 8', or on the hub of the crank connection with said axle, a spring influenced pawl 27 engaging with 60 the said ratchet thereby locking the crank and the rollers against reverse movement.

It will be obvious that only a single pair of superposed rolls may be utilized, but it is preferable to provide two pair of rolls so as 65 to permit of the simultaneous sharpening of both edges of a blade having a double cutting edge and thereby facilitate the sharpening of blades of this type.

If desired my device may be utilized as a 70 combined honing and stropping device, for which purpose each pair of rolls is provided with a different abrasive surface. For instance, one pair of rolls, such as 7, 7' may be adapted for stropping, and may or may 75 not be provided with an abrasive material; that is, the leather covering may be oiled, or provided with oil and a very finely comminuted or powdered abrasive material, such as powdered emery, carborundum and 80 the like; while the leather covering of the rolls 8, 8' is provided with a coarser abrasive material and serves for honing purposes.

Variations may be resorted to within the scope of my invention and portions of the 85 improvements may be used without others.

Having thus described my invention I claim:

A sharpening device for double edged cutting blades, comprising in combination 90 two pairs of superposed abrasive rolls; a crank connected to one of the rolls; a train of gearing connected to the rolls whereby to rotate all of the rolls from the roll to which the crank is connected; a blade carrying 95 rocker projecting between the rolls; a cam connected to and rotatable with the lower roll of each pair; and cam followers connected to the blade carrier to rock the carrier as the rolls are rotated to cause one side 100 of each cutting edge of the blade to engage with one roll of each pair alternately with the engagement of the opposite side of each cutting edge with the other roll of each pair.

DAVID M. CARO.
